US00D606202S

(12) **United States Design Patent**
Banryu

(10) **Patent No.:** **US D606,202 S**
(45) **Date of Patent:** **** Dec. 15, 2009**

(54) **CART OF MEASURING APPARATUS FOR
ULTRASONIC DIAGNOSIS APPARATUS**

(75) Inventor: **Atsunobu Banryu**, Funabashi (JP)

(73) Assignees: **Kabushiki Kaisha Toshiba** (JP);
Toshiba Medical Systems Corporation
(JP)

(**) Term: **14 Years**

(21) Appl. No.: **29/334,665**

(22) Filed: **Mar. 31, 2009**

(30) **Foreign Application Priority Data**

Nov. 28, 2008 (JP) 2008-030538

(51) **LOC (9) Cl.** **24-02**

(52) **U.S. Cl.** **D24/185**

(57) **CLAIM**

The ornamental design for a cart of measuring apparatus for ultrasonic diagnosis apparatus, as shown and described.

DESCRIPTION

FIG. 1 is a front, top and right side perspective view of a cart of measuring apparatus for ultrasonic diagnosis apparatus, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.
